CLAIM

The ornamental design for an automated teller machine, as shown and described.

DESCRIPTION

FIG. 1 is a front, top and right side perspective view of an automated teller machine, showing our new design;

FIG. 2 is a front, top and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a cross-sectional view taken along line 9-9 of FIG. 3;

FIG. 10 is another front, top and right side perspective view thereof, shown in a used condition with environmental structure shown in broken lines;

FIG. 11 is another front, top and right side perspective view thereof, shown in a used condition with environmental structure shown in broken lines;

FIG. 12 is an enlarged view of the portion shown in the dot-dash line box labeled FIG. 12 in FIG. 1;

FIG. 13 is an enlarged view of the portion shown in the dot-dash line box labeled FIG. 13 in FIG. 2;

FIG. 14 is an enlarged view of the portion shown in the dot-dash line box labeled FIG. 14 in FIG. 3;

FIG. 15 is an enlarged view of the portion shown in the dot-dash line box labeled FIG. 15 in FIG. 12;

FIG. 16 is an enlarged view of the portion shown in the dot-dash line box labeled FIG. 16 in FIG. 12;

FIG. 17 is an enlarged view of the portion shown in the dot-dash line box labeled FIG. 17 in FIG. 12; and,

FIG. 18 is an enlarged view of the portion shown in the dot-dash line box labeled FIG. 18 in FIG. 12.

The evenly spaced dash lines represent environmental subject matter that forms no part of the claimed design. The
